Primary Examiner — Sheryl Lane*Assistant Examiner* — Emily A Caven(74) *Attorney, Agent, or Firm* — Lerner David LLP(57) **CLAIM**

The ornamental design for a litter tray, as shown and described.

DESCRIPTION

FIG. 1 is a perspective view of a litter tray showing my design.

FIG. 2 is a front view of the litter tray shown in FIG. 1.

FIG. 3 is a rear view of the litter tray shown in FIG. 1.

FIG. 4 is a left side view of the litter tray shown in FIG. 1.

FIG. 5 is a right side view of the litter tray shown in FIG. 1.

FIG. 6 is a top view of the litter tray shown in FIG. 1; and,

FIG. 7 is a bottom view of the litter tray shown in FIG. 1.

The broken lines illustrate portions of the litter tray and form no part of the claimed design.

1 Claim, 5 Drawing Sheets(56)
